CLAIM

The ornamental design for a portable energy storage and distribution device, as shown and described.

DESCRIPTION

FIG. 1 is a front perspective view of a portable energy storage and distribution device;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

In FIGS. 1-7, broken lines indicate environmental structure that forms no part of the claimed design.
